UNITED STATES PATENT OFFICE.

WILLIAM D. HARDEN AND JOSEPH P. WHITE, OF SAVANNAH, GA., ASSIGNEES
OF TWO-THIRDS TO SAID HARDEN AND ONE-THIRD TO SAID WHITE.

TOY VEHICLE.

SPECIFICATION forming part of Letters Patent No. 341,329, dated May 4, 1886.

Application filed October 1, 1885. Serial No. 178,741. (No model.)

To all whom it may concern:

Be it known that we, WILLIAM D. HARDEN and JOSEPH P. WHITE, citizens of the United States, residing at Savannah, in the county of Chatham and State of Georgia, have invented new and useful Improvements in Toy Vehicles, of which the following is a specification.

This invention relates to toy engines and other toy devices, comprising sectional parts and means for separating said parts in imitation of an explosion.

The invention has for its object to provide a novel toy of the above-mentioned character; and it consists in the combination, with a sectional toy having wheels to travel on a floor or other surface, of a device for effecting the separation of the toy-sections in imitation of a miniature explosion, and mechanism connected with the wheel-axle and held inoperative thereby while the wheels are stationary on the surface traversed, and operating only when the wheels travel on such surface to release or operate the aforesaid device.

The invention further consists of other features, which will be hereinafter fully described and claimed, reference being made to the accompanying drawings, in which—

Figure 1 is a side elevation of the locomotive-engine entire. Fig. 2 is a similar view showing the parts at the moment of explosion. Fig. 3 is a vertical longitudinal section of Fig. 1, showing the propelling and exploding mechanism in elevation. Fig. 4 is a sectional view of the exploding devices slightly enlarged. Fig. 5 is an inverted plan view of the removable section of the boiler and cab, showing the manner in which they are detachably united. Fig. 6 is a view of the exploding-cartridge. Fig. 7 is a central longitudinal section of a toy engine propelled by any device other than automatic mechanism, and embodying our invention. Fig. 8 is a detail showing a form of automatic exploding mechanism adapted to locomotives of the class shown in Fig. 7. Fig. 9 is a transverse section taken behind the shaft of the drive-wheels, showing a modification. Fig. 10 is a detail perspective of part of the devices shown in Fig. 9.

In the said drawings, the reference-numeral 1 designates the frame of a toy locomotive-engine, having pivotally-mounted pilot-wheels 2 and large driving-wheels 3, the construction being of the kind usually employed in this class of toys. The shaft 4 of the driving-wheels is driven by a train of gears, 5 6 7, &c., actuated by a coiled spring, 8, having one end attached to a winding-shaft, 9. This mechanism may be of any known or suitable description.

Upon the frame 1 is mounted a miniature boiler, 10, having miniature cylinders and piston-rods 11, a cab, 12, being placed behind the rear end of the boiler. Upon the forward end is mounted a smoke-stack, 13, connected with the boiler by a wire, 14, or similar device, hinged upon the end thereof and rigidly connected with the lower end of the stack, the extremity of which rests in an opening, 15, in the top of the boiler.

The upper portion or roof of the cab is severed by a horizontal cut from the lower portion, and the lower ends of the walls are provided with short forks 16, which straddle and rest upon the edges of the lower portion, whereby a secure union of said parts is effected, while at the same time the roof of the cab may be easily removed by lifting it upward.

A section, 17, of the boiler may be made detachable from the rest of said section, forks 18 being mounted upon its inner surface and projecting below its edges in such manner as to straddle and rest upon the edges of the permanent portion 10.

Within (or it may be placed under) the boiler, a little distance in front of the spring 8, is firmly mounted a small anvil, 19, having upon its upper part a breech-piece, 20, adapted to receive a blank cartridge, 21, which is preferably of about thirty-two caliber. Upon the lower part of the anvil is pivoted a hammer, 22, which is thrown against the cartridge by a spring, 23, which is connected to the hammer above its pivotal mounting by a finger, 24, curved upward, so that when the hammer is drawn back far enough the point of attachment of said finger will be carried below the

pivotal point of the hammer, thereby holding the latter cocked by the tension of the spring. The arrangement of these parts is such that when thrown back far enough to be cocked 5 the end of the hammer rests upon or lies near the spring 8, which is coiled to its smallest size and highest tension. The parts being in this position, and the cartridge 21 being inserted in the breech-piece, the roof of the cab 10 and the detachable section of the boiler and the smoke-stack are all placed in position, a bar, 25, rigidly mounted upon the former, projecting immediately over the steam-drum 26 upon the detachable boiler-section. The 15 engine is then placed upon the floor and released, whereupon the spring 8 sets the driving-wheels in motion and propels the locomotive. As the movement continues, the spring expands until it lifts the point of attachment 20 of the finger 24 above the pivotal point of the hammer 22, whereupon the latter is thrown violently against the cartridge, exploding it and throwing off the removable section of the boiler, which carries with it the roof of the 25 cab, and at the same time toppling the smoke-stack over in front, by which the engine is immediately stopped. The operation thus described can be repeated *ad libitum*.

We may make the boiler with more than one 30 removable section, and the parts may be connected in any suitable manner.

This invention may be applied without material change to a toy steamboat, and it affords a safe and entertaining means of amusement for children. The firing mechanism is 35 so arranged that there can be no danger to the person in case of a premature discharge, the entire force of the explosion being received by the closed forward end of the boiler.

40 The arrangement described and illustrated is deemed the best and most complete, and shows the character of the invention; but for the purpose of furnishing the toy at a cheaper price the explosive arrangement, substantially as described, may be attached to any 45 toy vehicle which represents a vehicle propelled by steam-power, but which is not automatically moved, but is moved by an external application of force, as by being pulled 50 with a string. In such case we propose accomplishing the same results by arranging on the revolving axle of the driving-wheels a screw-thread or spiral flange or similar device, which will move a sliding finger to the exploding 55 mechanism, and thus discharge the lock. The sliding finger should be movably attached to a fixed rod above the axle, and so arranged that it can be set at any point of the thread or spiral flange, and the movement of the axle, 60 as the vehicle is propelled, will cause the finger to slide on the rod and so discharge the exploding mechanism; and where it is desirable to have the toy used under circumstances where it would be preferable to avoid the 65 noise, smoke, and smell of an exploding cartridge, the same or a similar arrangement de-

scribed for discharging the hammer to explode the cartridge may be used to discharge a spring, which will fly up and throw off the detachable portions of the vehicle. This form 70 of construction is shown in Fig. 7, in which the invention is shown as applied to a toy locomotive having the detachable parts constructed substantially as already described.

In Fig. 7 we have illustrated the application of a spring for the purpose of producing such a dismemberment of the parts as to imitate a boiler-explosion, and in said figure the numeral 28 designates a steel spring of suitable strength mounted upon a block, 29, upon 80 the lower portion of the boiler. The end of this spring is free to vibrate vertically, and lies normally near the roof of the boiler and preferably near the base of the steam-drum when applied to a locomotive. Upon the removable boiler-section 17 is mounted an inner yoke-shaped strip, 30, arranged over the spring in such position that the latter will, when released from tension, strike smartly upon it and throw the removable boiler-section into 90 the air. The detachable roof 12 of the cab is thrown off by the bar 25, as already described, and in order to throw down the stack a bar, 31, is rigidly fastened to the base of the same and extended just above the boiler till its end 95 overlies the end of the boiler-section 17. The spring 28 is held at the required tension by a catch, 32, pivoted in a horizontal plane on a standard, 33, and having its rear end projecting over or near the rear axle, 34. Upon this 100 axle is mounted or formed a worm, 35, which is revolved by the movement of the toy, and straddling the axle in such manner as to engage with the worm is a removable trigger, 36, having at one end a fork, 37, which sits upon 105 the axle and meshes with the worm. In front of the trigger and above and parallel with the axle is placed a rigid bar, 38, against which the trigger rests as the worm revolves, and by which its upright position is preserved. The 110 spring 28 being bent and confined, the trigger is placed next to the right-hand drive-wheel, with its forked end engaging with the worm, and the engine is set in motion in any suitable manner. This motion causes the trigger to 115 travel slowly toward the opposite end of the axle until it impinges upon the end of the pivoted catch 32, which is turned by it far enough to release the spring 28 and cause the 120 miniature explosion. This form of construction effects the result proposed without the use of powder, and avoids the smell of the smoke and noise of the explosion. We propose, however, to apply the firing mechanism in a slightly-modified form to the automatic 125 explosion of a cartridge in toy devices moved by external force—such, for example, as a string, by which it may be drawn.

One form of the devices last mentioned is illustrated in Figs. 9 and 10, in which the 130 numeral 20 denotes the breech-block, (shown in Figs. 2, 3, and 4,) with its hammer 22 con-

structed and actuated in the manner already described. The hammer, when cocked, rests upon one end of a lever, 39, pivoted upon a horizontal axis, 40, and having the other end, 5 40°, bent at an angle, so as to lie over or near the axle 34, which is provided with a worm, as already described. The trigger used with this lever is provided with a point, 41, having a beveled or inclined edge adapted to engage 10 with and by its advancing movement depress the end 40° of the lever, and thereby lift the hammer high enough to spring it. The trigger is supported and guided by a bar, 38, which also affords a support for the lever 39, the bent 15 end of which underlies said bar, and thereby enables the lever to support the hammer when cocked. The construction of the trigger is in all respects, save its beveled or cam edge, similar to that shown and described in connection 20 with Figs. 7 and 8. The end of the hammer 22 is slotted and receives a rest, 42, pivoted in the slot or fork, which may be turned to support the hammer, when cocked, at varying heights, and thereby enable it to be more easily 25 sprung.

We are aware that sectional toy engines and other toys have been provided with means whereby the parts may be separated in imitation of an explosion; but we are not aware 30 that a sectional toy has ever heretofore been provided with wheels to travel on a floor or other surface combined with a device or devices for effecting the separation of the toy-sections, and means connected with the wheel 35 axle and held inoperative when the wheels are stationary on the floor or other surface traversed, but permitted to operate and actuate the device which separates the toy-sections when the toy is traveling over the floor or 40 other surface.

Having thus described our invention, what we claim is—

1. The combination, with a sectional toy having wheels to travel on a floor or other 45 surface, of a device for effecting the separation of the toy-sections in imitation of a miniature explosion, and mechanism, substantially as described, connected with the wheel-axle and held inoperative thereby, while the wheels are 50 stationary on the surface traversed, and operating only when the wheels travel on such surface, substantially as described.

2. The combination, with a toy locomotive or other steam-engine having removable boiler 55 and cab sections and a movable stack, of cartridge-exploding mechanism located within or under the boiler, and operated by the propelling mechanism of the engine, substantially as described.

60 3. The combination, with a toy locomotive or other toy steam-engine having one or more removable boiler-sections and a removable

roof or other top portion of the cab, of a smoke-stack hinged to or detachably mounted upon the outer end of the boiler and seated in 65 an aperture in the top thereof, and cartridge-exploding mechanism located within or under the boiler and automatically operated by the propelling mechanism, substantially as described.

4. The combination, with a toy locomotive or other toy steam-engine, of cartridge-exploding devices located within or under the boiler, propelling mechanism whereby said exploding devices are actuated, a removable boiler-section, 70 and a cab-roof or other top portion, each having forks which straddle and rest upon the edges of the permanent portion, and a stack hinged to the boiler and resting in an opening in the top thereof, the cab-roof having 75 a bar which projects over the steam-dome on the removable boiler-section, substantially as described.

5. In a toy locomotive or other toy steam-engine having removable boiler-sections and 80 smoke-stack, the combination, with a train of gearing and a mainspring driving the wheels, of a breech-piece located in the boiler, and a hammer, which, when cocked, rests upon or near to the compressed propelling-spring, 85 substantially as described.

6. In a toy locomotive or other toy steam-engine, the combination, with the boiler having one or more removable sections, of a cab having a removable roof or other portion, 90 provided with a bar projecting over the steam-dome mounted on one of said sections, a breech-piece located within or under said boiler, and a hammer operated by a spring connected with said hammer by a curved finger, and a propelling-spring against which the 95 hammer lies when cocked.

7. In a toy locomotive or other toy steam-engine, the combination, with a propelling-spring actuating a train of gears, of a boiler 105 constructed with one or more removable sections having forks which straddle and rest upon the edges of the permanent parts, a stack resting in an opening in the boiler and connected with the end thereof by a hinge-joint, 110 a breech-piece within or under the boiler, a hammer pivoted theron, and a curved finger connecting said spring to the hammer above its pivotal point, the hammer being arranged so that when cocked it lies upon or near to the 115 compressed propelling-spring, substantially as described.

In testimony whereof we affix our signatures in presence of two witnesses.
